UNITED STATES PATENT OFFICE

CARLYLE D. READ, OF HAMMOND, INDIANA, ASSIGNOR TO STANDARD OIL COMPANY,
OF WHITING, INDIANA, A CORPORATION OF INDIANA

PETROLEUM TAR

Application filed June 23, 1927. Serial No. 201,004.

This invention relates to petroleum tars and particularly pressure tars which result from a cracking process operated at high temperatures and a substantial pressure.

5 The invention will readily be understood from the following description in connection with the accompanying drawing which shows diagrammatically an apparatus whereby the pressure tar may be produced and treated according to the invention.

10 Referring to the drawing, 10 is a heating coil; 11 is a retort or conversion chamber; 12 is a reflux condenser for overhead from said chamber; 13 is a flash-drum for tar 15 from chamber 11; 14 is a filter for the residue from said flash-drum; 15 is a fractionating condenser for the overhead from the flash-drum; 16 is a receiver for the heavy condensate therefrom; 17 is a liming tank 20 in which a portion of said condensate is adapted to be charged with lime; and 18 is a feed-pipe leading to the heating coil 10.

A pump 19 is provided for supplying charging stock under pressure to the heating coil 10. The outlet 20 of the heating coil 10 leads into the conversion chamber 11, which is maintained at a desired cracking temperature by burners 21. The conversion chamber 11 is suitably provided with a 25 scraper 40 for the purpose of removing coke forming material from the walls thereof and causing it to fall to the bottom of the chamber. From the upper end of the conversion chamber 11 a vapor pipe 22 leads to the reflux condenser 12, which may be provided with suitable fractionating and condensing devices (not shown). A vapor pipe 42 leads from the top of the fractionating condenser 12 to a suitable condenser (not shown). 30 Reflux condensate may be returned from condenser 12, through line 23 by pump 23^a to the heating coil 10. From the lower end of the conversion chamber 11 a pipe 24 leads to the flash-drum 13, said pipe 24 being provided with a valve 25. From the top of the drum 13 a pipe 26 leads to the lower part of the fractionating condenser 15 which is provided with suitable fractionating and condensing devices (not shown). From the 35 base of this condenser a pipe 27 leads into

the receiver 16 and from the top thereof a pipe 43 leads to a suitable condenser (not shown). From the underside of the drum 13 a pipe 28 leads into the filter 14. A suitable pump, for example, a hot oil pump, 29 is provided in the line 28 for forcing the pressure tar residuum into the filter 14. The filtered pressure tar residuum passes from the filter 14 by pipe 30.

55 The heavy pressure tar distillate receiver 16 is provided with a valved outlet 31 and an outlet 32 which leads into the bottom of the liming tank 17. A pump 33 is provided in the line 32.

60 The liming tank 17 is provided with a 65 perforated pipe 34 which is adapted to inject air into the contents thereof. From a low position on the tank 17, a pipe 35 leads to the upper portion of said tank. Said pipe 35 is provided with a circulating pump 36 70 and a hopper 37 by means of which lime and other substances, such as water, may be added to the oil circulated by pump 36 and may thereby be disseminated throughout the oil in tank 17. From the bottom of tank 17, a 75 pipe 38 leads into the feed-line 18. A pump 39 is provided in the line 38.

75 The operation is as follows:

Heavy pressure tar distillate is pumped 80 from receiver 16 through line 32 by pump 33 into tank 17 until it is nearly full. The distillate is then circulated through pipe 35 by pump 36 from the bottom to the top of the tank 17. Hydrated, powdered lime is fed 85 into the circulating oil by the hopper 37 and is carried by the circulating oil into tank 17. A certain amount of water is then supplied by hopper 37, said water assisting materially in the production of a satisfactory suspension or slurry of lime in the oil. While 90 the suspension is being produced and, also, preferably, while it is being used, the oil in the tank 17 is agitated by air introduced by the perforated pipe 34. It is preferred to produce in this manner a slurry of lime containing approximately 1.5 pounds per gallon. The amount of water used may suitably be about 0.8% by volume of the oil. This 95 method of mixing lime with the oil is not part of the present invention since it is de- 100

scribed and claimed in the patent application of Edward E. Bartels, Serial No. 204,435, filed July 9, 1927. The lime may be mixed with the oil in any other suitable manner, if desired.

The charging stock which is supplied to the heating coil 10 through line 18 by the pump 19 may be any suitable hydrocarbon oil heavier than gasoline, such as gas oil, pararaffin light ends, pressure tar distillate, heavy paraffin distillate, or mixtures of two or more thereof. Oil slurry is fed to the charging stock through line 38 by pump 39 in quantity sufficient to provide a suitable lime content in the oil passing through the heating coil 10 and the conversion chamber 11. A suitable quantity of lime is approximately 0.5 pounds per barrel of charging stock.

The temperature and pressure conditions in the heating coil 10 and the conversion chamber 11 may vary within wide limits. For example, the outlet temperature of the heating coil 10 may suitably be about 820 to 850° F. and the pressure may suitably be about 325 to 400 pounds per square inch. The chamber 11 may be heated by the burners 21 to maintain a suitable cracking temperature therein.

The fractionating condenser 12 is controlled to give a pressure distillate of the desired character, the vapors of which pass off by pipe 42, and are condensed. The reflux from condenser 12 is returned to the heating coil 10 through pipe 23 by pump 23a.

Pressure tar is drawn off from the bottom of chamber 11 and is accompanied by more or less coke which is produced in the oil, as well as lime and calcium sulfide which are disseminated in solid form in the coke and in the tar. The withdrawal is effected continuously, or periodically, through the valve 25 and pipe 24 and the tar is flashed in the drum 13 which is maintained substantially at atmospheric pressure. The overhead passes by a pipe 26 to the fractionating condenser 15 in which the heavy pressure tar distillate is condensed, the condensate passing by pipe 27 to the receiver 16. The light pressure tar distillate vapors pass by pipe 43 to a suitable condenser (not shown).

Ordinarily, only a small part of the heavy pressure tar distillate is used in the tank 17 for the production of the oil slurry; the remainder is withdrawn by pipe 31 to be used in producing blended charge stock.

The pressure tar residue is pumped in a hot condition through pipe 28 by pump 29 into the filter 14. Ordinarily, it is preferred to use a pressure filter but any other suitable filter may be used. Among others, filters of the Sweetland and Kelly type are suitable. The filter surfaces may suitably be constituted by woven metal, such as fabrics woven from

steel, copper, brass, or other suitable metallic wire.

If desired, the lime may be introduced into the pressure tar otherwise than above described. For example, a slurry of lime in oil, preferably reduced pressure tar, may be introduced into the reduced pressure tar in pipe 28 by a pipe 41 immediately before said tar enters the filter 14.

The lime exerts two effects which aid materially in the satisfactory production of filtered pressure tar residuum. On the one hand, the lime neutralizes acidic substances which would otherwise be present in the pressure tar, thereby preventing corrosion of the filter and particularly the metal filter surfaces. On the other hand, the lime and carbonaceous matter together form readily filterable agglomerates, and also the lime itself constitutes, together with the coke, a suitable filter medium which materially aids in preventing passage of other solid material while permitting the liquid constituents to pass.

During the process the lime is converted, more or less completely to calcium sulfide and probably other calcium compounds are formed. The term "lime" in the appended claims is therefore intended to be understood generically to include calcium oxygen compounds, calcium sulfides and other calcium compounds.

Although the present invention has been described in connection with the details of a specific embodiment thereof, it is not intended that such details should be regarded as limitations upon the scope of the invention, except in so far as included in the accompanying claims.

I claim:

1. The method of producing pressure tar free from coke and other objectionable solid materials which comprises adding lime to a hydrocarbon oil and subjecting such oil to cracking to produce vaporous products and unvaporized pressure tar containing lime and carbonaceous matter in readily filterable agglomerates, separately withdrawing the said pressure tar and forcing the same through a filter medium, thereby removing the agglomerated lime and carbonaceous matter.

2. The method of producing pressure tar free from coke and other objectionable solid materials which comprises adding lime to a hydrocarbon oil and subjecting such oil to cracking to produce vaporous products and unvaporized pressure tar containing lime and carbonaceous matter in readily filterable agglomerates, separately withdrawing the said pressure tar and forcing the same through a metallic filter medium, thereby removing the agglomerated lime and carbonaceous matter.

3. The method of producing non-acid reduced pressure tar free from solid carbon and other solid materials which comprises admixing lime with a hydrocarbon oil and sub-

jecting such oil to cracking under pressure, separately withdrawing vaporized and unvaporized products, reducing the pressure upon said liquid products to effect vaporization of the lighter constituents thereof, thereby producing a reduced pressure tar containing said lime and carbonaceous matter in readily filterable agglomerates, and passing the said pressure tar while in heated condition through a filter medium to separate therefrom lime, coke and other solid materials, thereby removing the agglomerated lime and carbonaceous matter.
